UNITED STATES PATENT OFFICE.

SIMON COOPER, OF BROOKLYN, NEW YORK, ASSIGNEE TO THE McCALL COMPANY, OF NEW YORK, N. Y., A CORPORATION OF NEW YORK.

SHEET-WINDING APPARATUS.

Original application filed November 18, 1922, Serial No. 601,858. Divided and this application filed August 27, 1924. Serial No. 734,836.

To all whom it may concern:

Be it known that I, SIMON COOPER, a citizen of the United States, and resident of the borough of Brooklyn, county of Kings, and State of New York, have invented certain new and useful Improvements in Sheet-Winding Apparatus, of which the following is a specification.

This invention relates in general to paper handling machines and particularly to means for folding paper. The present invention is a division of my application, Serial No. 601,858, November 18, 1922.

My former application discloses means for simultaneously folding a number of superimposed sheets into a comparatively small compact package. The machine therein shown includes a magazine holding the numerous pieces constituting a complete garment pattern, a feeder having grippers adapted to pick the topmost sheets from a multiplicity of piles of sheets in the magazine, a means for moving these sheets to an operative point and engaging them with a wrapping arbor adapted to fold or wind the sheets into a long compact package, transfer mechanism arranged to remove the wrapped pack, rolls adapted to exert a pressure on the sheets and feed them to a device adapted to fold the elongated pack at right angles to the previously formed folds so as to deliver the multiplicity of sheets constituting a pattern from the machine in a single compact package. The present application is directed particularly to means for effecting one of the folding operations and the means for transferring the sheets after such folding.

An embodiment of the invention is illustrated in the accompanying drawings in which

Fig. 1 is a transverse section through a folding machine equipped with my improved sheet winding and pack transferring mechanism;

Fig. 1^a is a detail view;

Fig. 2 is a longitudinal section of the machine on line 2--2 of Fig. 1;

Fig. 3 is an enlarged detail illustrating the sheet feeding grippers and means for engaging the sheets fed thereby with the clamp of my improved sheet winding mechanism;

Fig. 4 is a detail view of a tucker blade;

Fig. 5 is a fragmentary detail illustrating another position of certain parts shown in Fig. 3;

Fig. 6 is an enlarged detail of the tucker blade shown in Figs. 3 and 5;

Fig. 7 is a longitudinal section through a sheet wrapping arbor and a certain mechanism related thereto;

Fig. 8 is a sectional view showing the arbor in collapsed position;

Fig. 9 is a fragmentary plan view of the arbor showing somewhat diagrammatically the related mechanism for stripping a pack of wrapped sheets therefrom;

Figs. 10, 11, 12, 13 and 14 are detail sectional views on an enlarged scale through the arbor at planes indicated by the correspondingly numbered section lines of Figs. 7 and 8;

Figs. 15 and 16 are details showing the arbor clamp in open and closed positions respectively;

Fig. 17 is a skeleton view illustrating the sheet wrapping arbor lock and a tension device co-operating with the arbor;

Fig. 18 is a fragmentary plan view illustrating means for engaging and disengaging the arbor driving mechanism;

Fig. 19 is a detail front elevation of the arbor driving mechanism.

Referring in detail to the drawings, the machine includes a magazine comprising a plurality of trays H which are adapted to support one or more piles of pattern sheets. The trays are superimposed and the forward edge of each is offset with respect to its neighbor and grippers or feeding fingers B supported on a carriage C are arranged to pick the topmost sheet from each pile on the trays and carry them to an operative station where the carriage will dwell for a sufficient length of time to permit the sheets to be engaged with my improved sheet winding mechanism.

The carriage C is provided with a tucker blade which, when the carriage arrives at a position adjacent with sheet wrapping or winding arbor, is actuated to engage the sheets with the arbor. The carriage supports near its upper end, guides 174 and 176 in which are slidably mounted bars 178 and 180 connected at their lower end by a

cross-bar 182 to which is secured a tucker blade 188 which blade is adapted to tuck or insert the several sheets between the jaws of the clamp 190 carried by the arbor D. The blade 188 is normally held in the upper position shown in Figs. 2, 3 and 4 by springs 192 secured at one end to said blade and at their other ends to the guides 174 and 176. The upper ends of the bars 178 and 180 are connected by a transverse rod 194 which rod is arranged to enter the forked ends 196 of a lever 198 when the carriage moves to its forward or lower position. The levers 198 are carried by a shaft 200 and means to presently be described are provided for rocking this shaft at the proper time to cause the tucker blade 188 to insert the sheets between the clamp jaws of the arbor D. The shaft 200 is supported in brackets 202 secured to the outside of the inclined carriage tracks. At one end this shaft carries an arm 204 connected by a link 206 with the free end of a lever 208 pivoted at 210 to a suitable boss formed on the frame 14. The lever 208 has a lower arm 212 carrying a roller 214 adapted to be engaged by a cam projection 216 formed on the rear face of a disc 218 carried by the shaft 138. A spring 220 normally holds the arm 208 in position to permit the rod 194 to freely enter the forked ends 196 of the levers 198 above referred to, a suitable stop 222 being provided to accurately position the parts. The active portion of the cam 216 is of very short length so that the sheets are quickly moved into engagement with the jaws 190 of the arbor D and the blade is quickly withdrawn from said arbor. Comparison of Figs. 3 and 5 illustrates the movement of the blade 188, but it is to be noted that in these figures only two sheets are shown as being moved into engagement with the arbor, but in practice it is to be understood that a much greater number of sheets are moved into such engagement, only two sheets being shown in this instance because the small scale of the drawing will not permit the clear showing of a great number. It might be here stated, however, that it is not absolutely necessary that each and every sheet be engaged by the arbor clamp as some of the smaller pieces of short length can be supported between other sheets of greater length. The winding arbor D as hereinbefore stated carries a clamp 190 between the jaws of which the multiplicity of superposed pattern sheets are inserted by the downward movement of the tucker blade 188. After such insertion the winding arbor is given a plurality of revolutions and then it is collapsed to permit the wrapped pack of sheets to be readily stripped therefrom. The construction and operation of the wind-

ing arbor will best be understood by comparison of Figs. 2 and 10 to 16.

The arbor is supported on a spindle 266 having enlarged portions 268 and 270 on which are fitted ball-bearings 272 and 274. These bearings are carried by a bracket 276 which is secured by bolts 278 to the side frame 10. On its outer end the spindle 266 has secured thereto a sprocket 280 which is connected by means of a chain 282 with a sprocket 284 (Fig. 1). The sprocket 284 is loosely mounted on a shaft 286 and is provided with a clutch face 288 adapted to contact with a clutch 290 (Figs. 1 and 18), which is rotatable with the shaft 286 and splined thereto so as to permit longitudinal movement. The shaft 286 carries a spiral gear 292 which meshes with a similar gear 294 carried by the main shaft 120, previously referred to. The shaft 120 it will be remembered rotates continuously and in order to intermittently rotate the sheet winding arbor and permit it to dwell at predetermined intervals. Means are provided to periodically shift the clutch 290 into and out of engagement with the clutch face of the sprocket 284. This clutch shifting mechanism includes a lever 296 pivoted at 298 to a suitable bracket secured to the side frame 10. This lever carries a pin at one end arranged to engage an annular groove formed in the clutch 290, and at its opposite end, said lever carries a pair of opposed rollers 299 which engage the opposite faces of a raised cam ridge 300 formed on a circular disc 302 secured to the shaft 114. It will be understood that the shaft 114 is continuously driven from the shaft 120 by means of the worm and gear 118 and 116. The cam ridge 300 is so shaped that the wrapping arbor will be periodically rotated so as to wrap the sheets thereon and it will cause the clutch 290 to be disengaged at the proper times to stop the wrapping movement so as to permit the sheets to be moved into engagement with the clamp 190 of the arbor while the same is at rest and will also permit the arbor to dwell, or remain stationary for a sufficient interval to permit the wrapped pack of sheets to be stripped from the arbor.

As shown best in Figs. 1 and 7, the arbor D is of considerable length and is supported only at one end. It is of small depth and as shown in cross section (Fig. 13) it is of minimum thickness. This proportion permits of wrapping wide sheets into a comparatively long narrow package as will be hereinafter more fully described.

The main body portion 304 of the arbor consists of an elongated hard wood member which is rigidly secured by means of bolts 306 and 308 respectively to a head portion 310 and brackets 312 carried by said head portion. The arbor includes a collapsible

- section 314 of substantially the same length as the portion 304. This section is pivoted on a stud 316 secured to the brackets 312. Springs 317 carried in suitable recesses 5 formed in the section 314 bear against guide plates 318 secured to the underside of the portion 304 of the arbor, and tend to move the section 314 to its expanded position, as shown in Fig. 7.
- 10 For collapsing the arbor a sliding member 320 is mounted adjacent the underside of the portion 304 and said member is formed with an upward extension 322 having a cam slot 324 formed therein which is adapted to co-act with a pin 326 secured to the upper end of a bracket 328 carried by the collapsible section 314. Comparison of Figs. 7 and 8 will show that the movement of the extension 322 to the left from the position shown 15 in Fig. 7 will cause the section 314 to be collapsed, that is to say, to be rocked on its pivot 316 to the position shown in Fig. 8. A spring 330 tends to pull the member 320 to the right and a dog 332 is provided to move the member 320 to the left. This dog is pivoted at 334 in a slot 336 formed in the head and a flange 338 which is integral with the head 310. One end of the dog engages a lip 340 formed at the left extremity of the 20 sliding member 320. The dog is rocked when its finger 342 is struck by the upper end of a tappet 344, to be presently described. This tappet performs a number of separate functions, one of which is to actuate the dog 332 as above described to effect the collapsing movement of the arbor, another of which is to lock the arbor in its correct position to receive the sheets to be folded and at the same time to effect the 25 opening movement of the arbor clamp. When the tappet 344 is in its lower position as shown in Fig. 7, the arbor is free to rotate and none of the parts thereof are effected by a tappet. However, when the 30 tappet is lifted to the position shown in Figs. 8 and 10 its upper end will move into the slot 336 formed in the flange 338 and thereby positively prevent rotation of the arbor as long as the tappet is in this position. As the tappet moves up it rocks the dog 332 as above described thus collapsing the arbor and a pin 346 secured to the tappet engages the offset end 348 of a striker 350 which is slidable in a suitable guide 352 secured to the head of the arbor. The upper end of the striker 350 is arranged to engage a pin or arm 354 which is secured to and extends laterally from a tube 356 forming one part of the clamp 190 previously mentioned. 35 This tube extends the full length of the arbor and is formed with a longitudinal slot 358 through which the pattern sheets are adapted to be inserted by the tucker blade 188. The tube 356 is prevented from moving endwise and its turning movement is 40 also limited by a pin 352 secured thereto which projects into a slot 353 formed in a curved plate 355 fixed to the arbor head as shown in Fig. 11. Side plates 360 and 362 of substantially the same length as the tube 70 45 356 are secured to the body portion 304 of the arbor and the upper ends of these side plates are formed to fit the cylindrical surface of the tube 356 and form sort of a bearing which permits the tube to rotate relatively to said plates. The opposed edges 364 and 366 of the plates 360 and 362 respectively are separated by such a transverse distance that the tucker blade 188 can insert the multiplicity of superposed sheets 50 between said edges and through the slot 358 in the tube 356, without binding or tearing the sheets. In other words the transverse width of the slot between the edges 364 and 366 is much greater than the combined thickness of the inserted portions of the sheets and the tucker blade. Fig. 10 shows the tucker blade in the act of inserting two superposed sheets into engagement with the clamp. It is to be understood, however, that a greater 55 number of sheets are inserted by the tucker blade, only two being shown because of the difficulty of illustrating a great number of sheets which are only actually a few thousandths of an inch in thickness. 95
- The closing movement of the clamp 190 is effected by a spring 368 one end of which is secured to the arm 354 carried by the tube 356 which constitutes the moving part of the clamp. The other end of the spring is anchored to a pin 370 carried by the flange 338 of the arbor head. As thus arranged it will be appreciated that the closing movement of the clamp is effected by the spring 100 which turns the tube 356 on its axis thereby pinching the inserted sheets between one wall of the slot 358 and the edge 366 of the plate 362. The opening movement of the clamp is effected when the tappet 344 moves up and lifts the slide 350 a sufficient distance to engage and rock the arm 354 carried by the tube 356. 105
- The mechanism for actuating the tappet 344 is best shown in Fig. 17 and includes a rocker arm 372 carried on a stud 374 which is secured to a suitable boss on the frame 10. This rocker arm carries a roller 376 on one end which co-acts with a cam 378 secured to the shaft 114 previously referred to. On its opposite end the rocker arm has a finger 380 adapted to engage a stud 382 secured to the tappet 344. The tappet is mounted for vertical movement in suitable guide brackets 384 and 386 which are secured to the side frame 10 in any suitable manner. A spring 388 is secured near the lower end of the tappet and tends to lift the same. The upper end of this spring may be secured to any fixed member. As shown in the drawings, however, the upper end of this spring is 110 115 120 125 130

conveniently anchored to a cross-shaft which has a comparatively small angular movement. The cam 378 is provided with suitable dwell portions which are proportioned to periodically hold the tappet 344 in its extreme upper and lower positions respectively.

From the above it will be clear that when the tappet moves upwardly the clamp 190 will be opened so as to permit the insertion 10 of sheets by the tucker blade, and the wrapping arbor D will be locked against rotation at this time due to the fact that the upper end of the tappet is within the slot 336 of the arbor head. It is also clear that 15 the movement of the tappet will rock the dog 332 so as to collapse the arbor. At the time the sheets are being inserted in the clamp this collapsing movement is really not necessary. After the sheets have been inserted 20 by the tucker blade and after the tucker blade has been lifted, the cam 378 causes the rocker 372 to depress the tappet and thereby unlock the arbor and permit the spring 368 to rock the clamp tube 356 from 25 the position shown in Fig. 10 to the position shown in Fig. 12, thus securely gripping the multiplicity of sheets to be wrapped. At this time the arbor is expanded, that is to say, the collapsible section 314 thereof is in 30 the position shown in Fig. 7. The clutch 290 will now be automatically shifted by the cam 300 so as to cause sprockets 284, 280, and chain 282 to rapidly turn the arbor through a sufficient number of revolutions 35 to wrap the superposed sheets into a long narrow pack as shown in Figs. 9 and 13. During this wrapping operation a tension web, to be presently described, is moved to such position that it prevents the free ends 40 of the sheets from flying about in haphazard manner.

After the sheets have been completely wound on the arbor the clutch 290 is disengaged by the cam 300 and lever 296. At 45 this time the cam 378 has turned to such position that the spring 388 is permitted to lift the tappet 344 which results in positively locking the arbor against rotation, rocks the tube 356 to the position shown in Fig. 15 50 so that the pack can subsequently be stripped from the arbor, and the dog 332 is rocked to retract the slide 320 thereby collapsing the arbor as shown in Figs. 8 and 14. This collapsing movement is important as it removes 55 the tension from the closely wound pack of sheets carried by the arbor, and thus permits them to be readily stripped by the transferring mechanism, hereinafter described.

60 The tension web which prevents the free ends of the sheets from flying about as the arbor is rotated consists of a fabric belt 390 of approximately the same transverse width as the length of the winding arbor. One 65 end of the tension web is secured to a cross

rod 392 and the other end of the web carries a tension weight in the form of a transverse bar 394, as best shown in Fig. 2. The bar 392 is supported at each end in a suitable loop formed in a flexible cable 396, the lower 70 end of which carries a weight in the form of a cross bar 398. Each cable 396 is trained over a guide sheave 400 near its lower end and over a similar sheave 402 near its upper end. The sheaves 400 and 402 are loosely 75 mounted on suitable cross-shafts as shown. The cable after passing around sheave 402 extends downwardly to the left and the extreme end thereof is secured to an arm 404 of a bell crank mounted on a shaft 406. 80 This bell crank also is provided with a second arm 408 which is connected by a pitman 410 with an arm 412 which is pivoted on cross-rod 414. The upper end of this arm is offset as shown at 416 and is provided with 85 a cross-bar 418 around which the tension web 390 passes. The arm 412 is in reality a bale-like member, the lower ends of which are pivoted on the rod 414 and the upper ends of which are joined by the cross member 418. The tension web 390 is also trained over a fixed cross rod 420 secured to suitable brackets not shown. For controlling the movement of the tension belt across the top of the winding arbor a cam 90 422 is provided on the shaft 138. This cam co-acts with a lever 424 secured to the shaft 406.

It will be perceived from the above description that when the cam 422 revolves, 100 the lever 424 will move clockwise thus moving the lever 404 clockwise which will permit the weight 398 to pull the cable 396 down so as to bring the cross-bar 392 across the top of the winding arbor substantially 105 to the position shown in Fig. 13. At the same time arm 408 and pitman 410 will withdraw the arm 412 so as to swing the cross bar 418 to the left from the position shown in Fig. 2 so as to permit the rotation 110 of the arbor without interfering with said cross-bar. It is apparent that with the web 390 extending across the top of the arbor, when the same is rotated a gentle yielding tension will be exerted on the sheets being wrapped. The amount of this tension can be varied by varying the weight of the respective tension weights 394 and 398. In addition to exerting a tension on the sheets being wrapped the web 390 and cross-bar 115 392 also serve as a guide when the sheets are being inserted into engagement with the clamp 190 of the wrapping arbor. At this time the carriage of course is in its lowermost position and the forward ends 120 of the several sheets are prevented from falling down into the interior of the machine after they are released by the gripper fingers by a sheet metal tray 426 which is supported on cross rods 428 and 430. The 125 130

upper ends of the released sheets will hang over the cross-bar 392 as shown in Fig. 3 and the extreme ends of some of the longer sheets will perhaps rest on the forward edges of the trays H. At this time the cross bar 392 and the cross member 418 will be substantially in vertical alignment and the portion of the tension web therebetween will naturally form a vertical guide wall which will assist the operation of neatly inserting the sheets between the jaws of the clamp 190.

Pack transfer mechanism.—After the several sheets have been wrapped on the arbor and the same has been collapsed a pair of opposed stripping jaws are moved so as to engage the opposite sides of the wrapped pack, these jaws are then moved longitudinally so as to move the wrapped pack into the bite of a pair of opposed rollers which will completely strip the pack from the collapsed arbor.

This mechanism is best shown in Figs. 1, 2, 9, 14, 17 and 18. The gripping jaws are formed of angle bars 432 and 434 secured to the free ends of arms 436 and 438 which are slidably mounted on cross-shafts 440 and 442. The jaws are provided with resilient pads 444 and 446 of rubber or other suitable material which engage the opposite sides of the wrapped pack as shown in Figs. 9 and 14. The arms 436 and 438 are arranged in pairs, that is to say, there are two arms 436 carried by the shaft 440 and two arms 438 carried by the shaft 442. Each pair of arms is connected at its upper end by the angle bar jaw 432 and 434 respectively. Near their lower ends the arms 436 are connected by a cross-rod 448 and the arms 438 are similarly connected by a cross rod 450. Rigidly secured to the shafts 440 and 442 respectively are short bifurcated arms 452 and 454 which slidably engage the cross-rods 448 and 450 carried respectively by the arms 436 and 438. This arrangement permits the arms 436 to partake of the rocking movement imparted by the shafts 440 and 442 and also permits said arms to be shifted longitudinally with respect to the shafts on which they are slidably mounted. The arms 436 and 438 as shown at the right in Fig. 1 are each provided with a lug 456 and each lug is connected by a link 458 with a rocker arm 460 pivoted on a rock shaft 462 mounted in suitable bearings 464 and secured to the base of the machine. Connecting the two rocker arms 460 is a rod 466 to which one end of a pitman 468 is connected. The other end of this pitman is pivotally secured at 470 (Fig. 1^a) to the arm 472 of a bell crank loosely mounted on a shaft 474 which is supported in suitable fixed bearings 476. The other arm 478 of the aforesaid bell crank, carries a cam roller 480 which rides in a cam groove 482 of a cam 484 secured to a shaft 486. This shaft carries a worm gear 488 (Fig. 1) which meshes with a worm 490 secured to a cross shaft 492. On the forward end this shaft carries a miter gear 494 which meshes with a similar gear 496 secured to the main drive shaft 120.

The shafts 440 and 442 have secured to their forward ends spur gears 498 and 500 respectively which mesh with one another as shown in Fig. 17. The shaft 442 carries an arm 502 which is connected by a pitman 504, the lower end of which is secured to an arm 506 of a bell crank pivoted on a fixed stud 508. The lower arm 510 of this bell crank carries a cam roller 512 which co-acts with a groove 514 formed in a cam 516 secured to the shaft 114.

The above connections provide means whereby the opposed jaws 432 and 434 move from the position shown in Fig. 2 to that shown in Fig. 14 so as to engage the wrapped pack of sheets wound on the arbor. This engaging movement is effected by the cam 516 which through the bell crank arms 510 and 506, pitman 504 and arm 502 rocks the shafts 440 and 442 in the proper direction to cause the closing movement of the stripper jaws. After the jaws have engaged the wrapped pack the cam 482 comes in play causing the arm 472 of the bell crank carried by the shaft 474 to swing to the right and thereby move the arms 436 and 438 longitudinally on their supporting shafts 440 and 442. This action moves the wrapped pack longitudinally with relation to the arbor D a sufficient distance to bring the forward end of said wrapped pack into the bite of a pair of opposed rollers 518 and 520 which are arranged to rotate on vertical axes located on opposite sides of the projected axis of rotation of the sheet wrapping arbor D. To guide the pack into the bite of the rollers 518 and 520 a flared sheet metal housing 522 is provided which is secured to a fixed bracket 528 as shown in Fig. 1.

The rollers 518 and 520 exert sufficient pressure on the pack of sheets wrapped by the arbor D to crease the folds thereof. These rollers also feed the elongated wrapped pack of sheets to a winding mechanism disclosed in my original application, Serial No. 601,858 above referred to, which is adapted to wind or wrap the pack of sheets in a direction at right angles to that in which it was formerly wrapped so as to form a neat compact package.

Though I have described with great particularity the certain specific instrumentalities for winding sheets exerting a tension while the latter are being wound and means for transferring, it is not to be construed that I am limited to the constructions and arrangements shown as various modifications may be made by those skilled in the

art without departing from the invention as defined in the appended claims.

What I claim is:—

1. A folding machine including a collapsible arbor adapted to simultaneously wrap a multiplicity of sheets and flexible means movable across the arbor for exerting a tension on the sheets being wrapped.
2. In a folding machine, a collapsible arbor comprising a flat main body and a movable section forming one edge thereof and means for moving said section relatively to the main body and a flexible tension member movable across the arbor.
3. In a folding machine, a collapsible arbor comprising a rotatably mounted flat body and a rigid section supported on a transversely extending pivot, means carried by said body for transmitting movement to said rigid section and means for simultaneously actuating the last named means and locking the arbor against rotation.
4. In a folding machine, an arbor adapted to simultaneously wrap a multiplicity of sheets into a pack, said arbor having a clamp to hold the sheets while the arbor rotates, means for opening and closing said clamp, means for moving the sheets into engagement with the clamp, a member arranged to exert a tension on the sheets as they are being wrapped on the arbor and means for periodically moving said tension member across one face of the arbor.
5. In a folding machine, an arbor adapted to simultaneously wrap a multiplicity of sheets into a pack, said arbor having a clamp to hold the sheets while the arbor rotates, means for opening and closing said clamp, means for moving the sheets into engagement with the clamp, a flexible web for exerting a tension on the sheets as they are being wrapped on the arbor and means for moving and positioning said web so that it serves as a guide when the sheets are being moved into engagement with said clamp.
6. In a folding machine, an arbor adapted to simultaneously wrap a multiplicity of sheets into a pack, said arbor having a clamp to hold the sheets while the arbor rotates, means for opening and closing said clamp, means for collapsing said arbor and means engaging the opposite sides of the wrapped pack for stripping it from the arbor after the arbor is collapsed.
7. A folding machine including an arbor adapted to simultaneously wrap a multiplicity of sheets and a flexible belt arranged to be periodically moved across the path of the said arbor for preventing the free ends of the sheets from flying as the latter rotates.
8. A folding machine including an arbor, means for rotating the same to wrap a sheet thereon and a flexible belt for exerting a gentle tension on the sheet being wrapped so as to prevent the free ends thereof from flying and means for moving one end of said belt across the face of the arbor.
9. In a machine of the class described a collapsible rotary wrapping device, automatically controlled means for intermittently driving the latter and automatic means for periodically locking and collapsing said wrapping device.
10. A machine of the class described, including a rotary wrapping device, automatic means for moving the sheet across the top of said device, means engaging an intermediate portion of said sheet with said wrapping device so that it is doubled over when the wrapping device rotates.
11. In a machine of the class described, a flat rotary wrapping device, a clamp for engaging the sheets along one edge of said wrapping device, means for holding the sheets in engagement along the edge of said wrapping device and automatically actuated means for periodically locking the wrapping device.
12. In a machine of the class described a flat rotary wrapping device, means for moving sheets into engagement with said wrapping device and means extending along one edge of said device for holding the sheets in engagement with it and means for simultaneously locking said wrapping device and opening said holding means.
13. A folding machine having a wrapping arbor having a clamp along one edge and means for simultaneously pulling a multiplicity of sheets flatwise across the top of said arbor and means for engaging an intermediate portion of the sheets with said clamp.
14. A folding machine having a rotary wrapping element, means for simultaneously engaging the intermediate portion of a multiplicity of sheets with said element so that the sheets are wrapped in double plies as said element rotates.
15. A folding machine having a wrapping arbor and means for simultaneously pulling a multiplicity of sheets into a position in which their ends are on opposite sides of said arbor and means for buckling said sheets at about the center of their length for engagement with said arbor.
16. A folding machine including means for supporting a multiplicity of paper sheets, means for simultaneously feeding a number of said sheets to an operative station, a wrapping arbor, means for moving the central portion of the fed sheets into engagement with said arbor and means for rotating said arbor.
17. A folding machine including means for feeding a plurality of sheets to an operative station, a wrapping arbor in juxtaposition to said station, means for buckling said sheets to engage their central portions with said arbor, means for rotating said

arbor to wrap said sheets into a pack and means for stripping the wrapped pack from said arbor.

18. In a folding machine in combination with the mechanism for simultaneously feeding a multiplicity of sheets to an operative station, a flat arbor carrying a clamp, means for moving said sheets across the thin edge of said flat arbor and a blade carried by said feeding mechanism for engaging the sheets with said clamp, means for periodically rotating said arbor a plurality of revolutions, and a lock for positively holding said arbor in such position that its flat surface is substantially perpendicular to the plane of said sheets.

19. In a folding machine, an arbor adapted to wrap a multiplicity of sheets into a flat pack, said arbor having a clamp adapted to hold intermediate portions of the sheets as the arbor rotates, means for periodically rotating said arbor to wrap the sheets thereon, means for moving the sheets across the face of said clamp and means for periodically locking the arbor and accurately holding the clamp in position to receive the sheets and means for engaging said sheets with said clamp.

20. In a folding machine, an arbor having a sheet-engaging clamp comprising a fixed jaw and a movable jaw, means tending to normally hold the movable jaw in closed position, means for periodically rotating the arbor for several revolutions and stopping it with the clamp in the same position and means for simultaneously locking the arbor in its stopped position and opening said movable jaw.

21. In a folding machine, an arbor having a sheet-engaging clamp comprising a fixed jaw and a movable jaw, means tending to normally hold the movable jaw in closed position, means for periodically rotating the arbor for several revolutions and stopping it with the clamp in the same position, means for simultaneously locking the arbor in its stopped position and opening said movable jaw, means for simultaneously feeding a multiplicity of sheets into juxtaposition to said arbor and means for moving the sheets into position to be engaged by said jaws.

22. In a folding machine, an arbor having a sheet engaging clamp comprising a fixed jaw and a movable jaw, means tending to normally hold the movable jaw in closed position, a constantly rotating shaft, means for transmitting motion of said shaft to said arbor including a clutch, means for periodically shifting said clutch to interrupt the rotation of said arbor and a lock for positively stopping the arbor in a predetermined position, and means operating in synchronism with said lock for opening said movable jaw.

23. In a folding machine, a collapsible arbor adapted to wrap sheets, a clamp having a movable jaw adapted to hold the sheets in engagement with the arbor for buckling the sheets for engagement with said jaw and means for synchronously collapsing said arbor, opening said clamp and locking the arbor against rotation.

In witness whereof, I have hereunto signed my name.

SIMON COOPER.
